The ornamental design for a controller for an electric blanket, as shown and described.

(30) **Foreign Application Priority Data**

DESCRIPTION

Aug. 26, 2009 (JP) 2009-019521
Aug. 26, 2009 (JP) 2009-019522

FIG. 1 is a front elevational view of a controller for an electric blanket showing our new design;

(51) **LOC (9) Cl.** 13-03

FIG. 2 is a rear elevational view thereof;

(52) **U.S. Cl.** D13/168

FIG. 3 is a top plan view thereof;

(58) **Field of Classification Search** D6/595,

FIG. 4 is a bottom plan view thereof;

D6/596, 601, 602, 603, 605; 5/482, 485,
5/488-491, 494-502, 907; 219/212, 528;

FIG. 5 is a right side elevational view thereof;

D13/168

FIG. 6 is a left side elevational view thereof; and,

FIG. 7 is a cross-sectional view taken along line 7—7 in FIG. 1.

See application file for complete search history.

The connecting cord is shown broken away with broken lines to indicate indeterminate length.
